UNITED STATES PATENT OFFICE.

CHARLES SCHWEIZER, OF BOSTON, MASSACHUSETTS.

IMPROVEMENT IN ENVELOPES AND LETTER-SHEETS COMBINED.

Specification forming part of Letters Patent No. 131,184, dated September 10, 1872.

Specification describing certain Improvements in Combined Letter-Sheets and Envelopes, invented by CHARLES SCHWEIZER, of Boston, in the county of Suffolk and State of Massachusetts. The drawing accompanying this specification represents, in—

Figure 1, a diagram of my combined letter-sheet and envelope as developed upon a plane surface for writing; and in Figs. 2 and 3, opposite side views of the same as folded and sealed for the post.

My improved combination letter-sheet and envelope is formed from one piece of paper; and consists, first, of a rectangular portion, A, upon which writing is to be transcribed, and a second portion, B, consisting of two end flaps, *a a*, and a side flap, *b*, these flaps being so disposed as, when the sheet A is folded into the intended compass, they shall partially overlap one side thereof and one another, as shown in Fig. 2 of the drawing. The end flaps or wings *a a* are of sufficient width to partially overlap the front or address side of the folded sheet, as shown in Fig. 3 of the drawing.

The result of this arrangement is that the end flaps can be sealed and secured at the bottom to the envelope, and thus greater se-

curity is obtained without fastening the bottom edges of the flaps to the letter, which it would be necessary to do were not the flaps of such length as to permit of their being folded over upon the address side of the envelope.

By means of a combined letter-sheet and envelope, as before explained, an envelope is always at hand, as the two are inseparable, and for travelers especially the invention will be found valuable.

By my method a perfect envelope independent of the letter-sheet may be obtained, if desired, by removing the envelope portion B of the papers and cementing its edges.

Claim.

I claim as my invention—

The herein-described combined letter sheet and envelope, provided with flaps *a* arranged to fold over at the bottom onto the address side of the envelope, substantially as and for purposes stated.

CHARLES SCHWEIZER.
